UNITED STATES PATENT OFFICE.

LOUIS PAUL BRANDT, OF BIENNE, SWITZERLAND, ASSIGNOR TO LOUIS BRANDT & FRÈRE, OF SAME PLACE.

STEM-WINDING WATCH.

SPECIFICATION forming part of Letters Patent No. 534,780, dated February 26, 1895.

Application filed October 18, 1894. Serial No. 526,269. (No model.)

To all whom it may concern:

Be it known that I, LOUIS PAUL BRANDT, a member of the firm of Louis Brandt & Frère, watch-manufacturers, of Bienne, Switzerland, 5 have invented new and useful Improvements in Stem-Winding Watches, of which the following is a specification.

The invention consists of an improved device for the transmission of the rotation of 10 the stem of stem-winding watches of any system or construction whatever either to the winding-up or to the hand-setting-mechanism.

In the accompanying drawings my improved device is shown in both positions for the hand- 15 setting and for the winding-up of the watch.

Figure 1 shows the device in position for the winding-up. Fig. 2 shows it in position for the hand-setting. Fig. 3 is an enlarged detailed view of some of the working parts of 20 my device.

G is the stem upon which is disposed the winding-up wheel c which is intended to act upon the usual gear-wheels (not shown) causing the winding-up of the main-spring.

25 C is the usual sliding pinion, mounted upon a square portion of the stem G and provided with click-teeth c' intended to act upon the corresponding click-teeth c² of the above-mentioned wheel c which is free upon the said 30 stem G. The sliding-pinion C is further provided with a teeth-range c³ into which engages a gear-wheel d which is pivoted to the arm b³ of the rocking-lever B as described below.

35 A spring B' tends to maintain the rocking-lever B in the rest-position shown in Fig. 1.

My device is composed of a rocking-lever B pivoted at b to the plate A and guided by means of a screw b^x passing through a slot b' 40 pivoted to the said lever B and fixed to the plate A. The arm b³ of said lever engages in the circular groove c⁴ of the sliding-pinion C and the arm b³ bears the gear-wheel d, which is intended to act upon the usual handsetting- 45 wheel D. There is further provided a rocking lever E pivoted at e to the plate of the watch. The arm e' of said stem E is provided with a suitable projection engaging a circular groove of the stem G. If one throws the said 50 stem G in the sense of the arrow of Fig. 1 it causes the lever E to be rocked into the posi-

tion shown in Fig. 2 in which its other arm e² bears against the notched end of the arm b² of the lever B, as shown in Fig. 2, thus throwing the gear-wheel d into gear with the minute-wheel D and releasing at same time the click-teeth c' of the sliding pinion C from the click-teeth c² of the winding-up wheel c.

55 In order to secure the rocking-lever E, either at rest or in its acting position, I provide a stopping-spring or brake F fixed to the plate A and passing beneath the rocking-lever E. The end of said spring is bent upward and constitutes a catch f against which bears the arm e² of the lever E when the said lever E is 60 at rest as shown in Fig. 1.

When the lever E is acted upon as above specified by throwing the stem G in the sense of the arrow for the purpose of setting the hands, the said lever is obliged to pass over 70 the projection f, depressing the same and compressing at same time the spring F. The stroke of the lever E is limited by the arm b² as shown in Fig. 2 and the spring F is then kept compressed, its bent end f pressing 75 against the lower face of the arm e² of lever E and acting as a brake upon the same so as to prevent its too freely displacing.

Having thus described my invention, I 80 claim—

In hand-setting watches, the combination of a stem G, a rocking-lever B provided with two arms b² and b³ and acting upon a sliding-pinion C of usual construction, and of a rocking-lever E having two arms e' and e², 85 with a stop- or brake-spring F so disposed that its hooked end f engages the notched end of the arm b² of the lever B and hooks itself to the side of the arm e² of the rocking-lever B when the mechanism is at rest, and that its 90 said end f acts like a brake upon the lower face of said arm e² when the lever E is rocked into the position in which it bears with its arm e² in the notched end of the arm b² of lever B, substantially as shown and described. 95

In testimony whereof I have signed my name to this specification in the presence of two subscribing witnesses.

LOUIS PAUL BRANDT.
